M. E. SMITH.

BOILER

Filed Feb. 12, 1925

FIG. 1.

FIG. 2.

FIG. 3.

Mark E. Smith Inventor

By W. L. Land
Attorney

UNITED STATES PATENT OFFICE.

MARK E. SMITH, OF ERIE, PENNSYLVANIA, ASSIGNOR TO UNION IRON WORKS, OF ERIE, PENNSYLVANIA, A CORPORATION OF PENNSYLVANIA.

BOILER.

Application filed February 12, 1925. Serial No. 8,699.

This invention relates to a type of boiler having one drum superimposed directly over another drum. Ordinarily such drums have been permanently attached together forming a single unit. The present invention is directed to making this connection detachable so that the boilers may be more readily handled and more readily installed in place. Other features and details of the invention 10 will appear from the specification and claims.

The invention is illustrated in the accompanying drawings as follows:—

Fig. 1 shows a side elevation of the boiler.
15 Fig. 2 a section on the line 2—2 in Fig. 1.

Fig. 3 a plan view of the connection between the drums.

The boiler is shown in its usual setting for the furnace 1. A lower drum 2 is considerably shorter than the upper drum and is arranged directly back of the furnace. It is provided with flues 3 leading directly from the furnace to a smoke chamber 4 at the rear of the furnace. An upper drum 5 20 is provided with flues 6 leading from the chamber 4 forwardly to smoke box 7 and the smoke box is provided with the usual stack opening 8.

A ring 9 is shaped to conform to the outer surfaces of the shells at points between the shells and the shells are provided with openings 10, the openings in the two shells being in register and surrounded by the rings 9. Rods 11 extend through the rings, these 35 rods having heads 12 which are arranged in sockets 13 in the upper faces of the rings. The rods extend through the lower shell and are secured by riveting at 14. The upper ends of the rods extend through the shell 40 of the upper drum and through ring segments 16. Nuts 17 are arranged on the upper ends of the rods and these exert sufficient pressure on the shell to secure the joint between the shell and the ring 9. Preferably there are two of the rings between the two shells. These parts are shipped detached and handled detached so that they can be more readily handled and put in places difficult of access.

50 After the parts are in place the final attachment is made by the operator entering through the usual man-hole 18 for accomplishing the setting of the rings 16 and

the clamping nuts 17. Gaskets or caulking sheets 15 are arranged between the rings 9 55 and the surfaces of the shells. This makes a very economical setting and a very economical type of boiler and with its detachable sections makes it convenient to ship and possible to use it in places where it would be 60 impossible with the unit structure of boiler.

What I claim as new is:—

1. In a boiler, the combination of a lower drum; an upper drum, the upper drum having an opening in register with an opening 65 in the lower drum; a ring between the drums surrounding the openings, said rings having perforations with sockets leading to the perforations from one face of the ring; rods extending through the perforations and the 70 shells of the drums, said rods having shoulders arranged in the sockets; and means securing the rods to the shells, said means within one of the shells drawing the shoulders into clamping engagement with the bottoms of the sockets.

2. In a boiler, the combination of a lower drum; an upper drum, said drums having opposing openings; a ring arranged between the drums and having a wall surrounding 80 said openings, said ring making a fluid tight closure contact with the surfaces of the drums forming a nipple connection between the drums, said drums and nipple having registering openings extending through the 85 walls of the ring and the drums; and securing means extending through said registering openings and having heads within the shells.

3. In a boiler, the combination of a lower 90 drum; an upper drum, said drums having opposing openings; a ring between the drums, the walls of the ring forming a fluid tight joint with the walls of the drums around the openings and forming a nipple 95 connection between the drums, said ring and drums having registering openings extending through the walls of the ring and the drums, and rods securing the ring to one of the drums and detachably securing the 100 opposing drum to the ring.

4. In a boiler, the combination of a lower drum; an upper drum, said drums having opposing openings; a ring between the drums, the walls of the ring forming a fluid 105 tight joint with the walls of the drums

around the openings and forming a nipple connection between the drums, said ring and drums having registering openings extending through the walls of the ring and the drums; and rods engaging the ring and being headed over within one of the drums permanently securing the ring to one of the

drums and having nuts on the ends of the rods within the other drum for detachably securing the other drum to the ring. 10

In testimony whereof I have hereunto set my hand.

MARK E. SMITH.
